UNITED STATES PATENT OFFICE.

WILLIAM B. ROBINS, OF CINCINNATI, OHIO.

LAMP.

SPECIFICATION forming part of Letters Patent No. 239,061, dated March 22, 1881.

Application filed October 26, 1880. (No model.)

To all whom it may concern:

Be it known that I, WILLIAM B. ROBINS, of Cincinnati, Hamilton county, Ohio, have invented a new and useful Improvement in Lamps, of which the following is a specification.

A material feature of my invention relates to a construction of Argand lamps (the chimney of such lamps being omitted) in which the cylindrical passage constituting the interior draftway is of considerably greater diameter than hitherto customarily employed in such lamps. This unusually large diameter of draftway necessitates the use of a central deflector or button of corresponding dimensions. Such considerable diameter of deflector enables its adaptation to uses entirely unknown to and impossible with the ordinary small deflecting-button. For example, it may be so formed as, in addition to its accustomed duty of directing the interior draft-air against the flame, to also reflect the light thereof with various pleasing and useful effects. Such light-reflecting air-deflector may be composed of nickel-plated or other polished metal, or of glass or porcelain, and when of glass may, as to a part or all of it, be of opaque, transparent, or translucent stock, and be silvered or gilded, in whole or part, and either interiorly or exteriorly.

Associated with the above feature is a form and arrangement of wickway and two controlling adjustable sheaths or guards, by which is secured a very extended and at the same time very low and even flame, burning with perfect combustion without the necessity of a chimney, and under complete control. In association with such wickway and sheaths I employ, preferably, a wick consisting of two parts or wick-sections, of which the lower or conducting wick rests on the bottom of the font, and, being carried a proper distance up the wickway, supports the upper or burning wick. Of these sections the conducting-wick may be of any customary wick material, and the burning-wick is preferably of bibulous paper.

In order to stiffen the upper wick-section and to restrict the escape of inflammable vapor to its top edge, its entire vertical surfaces are coated or glazed with some adhesive substance that is insoluble in the burning-fluid—such, for example, as dextrine, mucilage, or

flour-paste. Such insoluble, impermeable, and adhesive glazing I further prefer to render incombustible and moderately friable by the addition of finely-pulverized steatite, asbestos, silica, or other refractory material; but inasmuch as I purpose making such wick the subject of a separate application for patent, no more specific description is requisite in this.

Associated or not with the above features may be a wickway rising vertically flush with the extreme outer periphery of the annular font. This arrangement is for some purposes of illumination preferred by me to that shown in Figure 1, in which a portion of the font extends outside of the wickway.

In order that the invention may be fully understood, I will proceed to describe it with reference to the accompanying drawings, in which—

Fig. 1 is a partly-sectional elevation of a lamp embodying all the above features of my invention except the marginal wickway. Fig. 2 is a top view of the same without the dome. Fig. 3 represents one of my improved burning-wick sections. Fig. 4 is a partly-sectional elevation of that form of my lamp where font is included wholly within the circuit of a marginal wickway.

A represents an annular font or reservoir for the burning-fluid, whose inner wall, B, is prolonged upward, as shown, so as to constitute one side or wall of a wickway, C, whose outer wall consists of a similar and concentric plate, D, of equal height, and whose portion included within the font is perforated to permit access of oil to the wick. The diameter of the inner cylindrical wall, B, of the annular wickway is such as to afford a central draftway, E, of unusually large diameter.

My wick, having been once inserted, remains undisturbed, and the height of the flame is regulated by two concentric sheath-plates, of which one plate, F, is located nearer to, and the other plate, G, is located more distant from, the common center than the wickway itself. Means are provided for the independent elevation and depression of these sheath-plates. For the inner sheath, F, my preferred means is a screw, H, which, being journaled at the lamp-axis in a hub, I, connected to the font by braces J, is tapped within a nut, K,

having brace-connections L with the inner sheath, F. For the outer sheath, G, my preferred means of elevation are spiral edges g, (of which one such edge is seen in Fig. 1,) which edges rest upon stumps or projections M on the wickway side. Two handles, N N', upon the sheath G enable it to be shifted circularly to right or left, so as to elevate or depress it uniformly around its circuit.

10 For the purpose of concentrating upon the inner face of the flame the air which ascends the interior passage or draftway, E, and by the same means reflecting the light with various striking and pleasing effects, I provide 15 a dome or cupola, preferably of glass, and which may have the form of a bell-glass, O. This dome rests upon the brace-connections L, and consequently rises and falls with the inner sheath. Lugs l on the braces L serve to 20 hold the dome to its proper concentricity with the sheath F, and consequently with the wickway. The dome O may be of metal, of porcelain, or of transparent, translucent, or opaque glass. It may be silvered, stained, or painted 25 on part or all of either its convex or concave surfaces. For example, being silvered on its crown merely, or zenith, with a transparent equatorial zone, it may be made to serve as a double reflector, reflecting upwardly and laterally from its convex surface and downwardly 30 through the draftway from its concave surface the rays which reach such surface through the transparent zone of the dome, so as to obliterate or neutralize the shadow cast by the font 35 and to make a practically shadowless lamp. The dome, being of opalescent, milky, or externally ground or frosted glass, may be stained or painted interiorly, so as to present on its exterior a pleasing semblance to the belt markings of Jupiter—a name which I propose to employ commercially by calling such zone-marked 40 form of my manufacture the "Jupiter lamp." When not so marked I prefer to designate it the "dome lamp."

45 P may represent a customary screw-capped feed hole or neck.

Q may represent an eye or socket to fit over a corresponding wall-bracket.

The wick employed by me consists prefer- 50 ably of two parts or sections—to wit, a lower section, R, called the "feed-wick," preferably of some woven fabric, such as is customarily employed for kerosene-lamp wicks, and resting upon such lower wick-section is an upper 55 section, S, preferably of blotting-paper, (bibulous paper,) from one to three sixteenths of an inch thick, whose entire vertical surfaces have been coated with some substance insoluble in hydrocarbons, such as dextrine, 60 mucilage, or flour-paste, so as, in effect, to convert the wick into a spongy tube or duct pervious only at its top and bottom edges, S' S", and its intervening interior portion. One effect of this construction of burning-wick is 65 to impart stiffness without impairing its transmeable qualities. Another effect is to pre-

vent the waste of fluid through the wick sides, and still another and important effect is to confine the combustion to the extreme summit of the wick, so as to secure a low, uniform, and intense flame.

The above-described illustration of my invention may be varied in form and arrangement of parts. For example, the light-reflecting draft-deflector may be of conical or conoidal form, so as to project more directly downward and outward against the inner side of the flame the central descending current of draft-air.

The wickway, with its adjustable sheaths, & its font, and deflector, may have an elliptical or a polygonal cross-section.

Fig. 4 represents an illuminating-lamp the outer wall of whose font is prolonged vertically upward to its summit. This form (preferred by me for many purposes) may be employed independently of the other useful novelties herein described, or in association with one or more of them.

The wickway herein illustrated is designed for a lamp suitable for burning kerosene or mineral oils. A lamp on the same principle may be adapted for animal or for vegetable oils by varying the height of the wickway in the inverse ratio of the density of the oil employed.

The illustrations are intended to represent what I designate a No. 12 dome or Jupiter lamp—that is, one having a wick-diameter of twelve inches.

I claim herein as new and of my invention—

1. A chimneyless lamp having two annular adjustable sheaths, F G, inclosing a stationary wick and wick-holder, substantially as set forth.

2. In a wide-draftway Argand lamp, the central draft-deflecting and light-reflecting dome or cupola, O, substantially as set forth.

3. In a wide-draftway Argand lamp, the central draft-deflecting and light-reflecting dome or cupola, O, in combination with its simultaneously-adjustable support, consisting of the interior wick-guard, F, substantially as set forth.

4. In a wide-draftway Argand lamp, the combination of concentrically-arranged central dome, O, and the wickway C, with its inclosing adjustable sheaths F G, for stationary wick, substantially as set forth.

5. In a wide-draftway Argand lamp, a central draft-deflecting and light-reflecting dome having one or more zones of diverse reflecting and translucent powers, substantially as set forth.

In testimony of which invention I hereunto set my hand.

WILLIAM B. ROBINS.
